UNITED STATES PATENT OFFICE.

EMIL A. NELSON, OF DETROIT, MICHIGAN, ASSIGNOR TO HUPP MOTOR CAR COMPANY, OF DETROIT, MICHIGAN, A CORPORATION OF MICHIGAN.

STARTING-CRANK.

1,108,212.

Specification of Letters Patent. Patented Aug. 25, 1914.

Application filed February 19, 1912. Serial No. 678,674.

To all whom it may concern:

Be it known that I, EMIL A. NELSON, a citizen of the United States of America, residing at Detroit, in the county of Wayne and State of Michigan, have invented certain new and useful Improvements in Starting-Cranks, of which the following is a specification, reference being had therein to the accompanying drawings.

10 The invention relates to starting cranks particularly designed for use in connection with motor vehicles, and the invention consists in various features of construction as hereinafter set forth.

15 In the drawings, Figure 1 is a sectional elevation of the crank; Fig. 2 is an end elevation thereof.

A is a tubular bearing mounted upon the frame of the vehicle (not shown) and forming a journal bearing for the revoluble crank B. The latter is formed of a bent rod having the portion C for engaging the bearing arranged in alinement with the engine shaft, the laterally extending portion D and 25 the handle portion E bent at right angles thereto.

To provide a simple construction of hand hold I employ a cup-shaped sheet metal member F, the body of which is adapted to 30 fit about the portion E and which at its inner end is provided with an outwardly extending flange G forming a hand-guard. This member is secured to the handle by suspending it over the same and forming an 35 inwardly extending head H engaging a neck portion I of the handle which is reduced in diameter. When the spun bead is formed it will be employed to disengage the member F from the handle while at the same time the 40 two parts are independently revoluble and thus the member F will not turn in the hands of the operator. Rattling of the parts is prevented by interposing a spring between the end of the portion E and the end of the 45 cupped member F and as shown, the spring J is located in a recess K in the end of the member E.

For holding the crank in its normal upright position a member L is mounted with a threaded engagement upon the bearing 50 member A and has pivotally secured thereto a fork or bifurcated member M adapted to drop into engagement with the handle D and lock the same. When the crank is in use the member M is turned upward out of 55 the way.

What I claim as my invention is:

1. The combination with a crank having an outwardly extending handle provided with a contracted neck portion, of a sheet metal member sleeved upon said handle having an outwardly-extending flange at its inner end forming a hand-guard and having a spun portion adjacent to said flange engaging the contracted neck portion of said 60 handle.

2. The combination with a crank having an outwardly extending integral handle and a contracted neck portion, of a cupped cylindrical sheet metal member sleeved upon said handle having at its inner end an outwardly extending flange adjacent to the crank, and an inwardly spun bead adjacent to said flange engaging the contracted neck portion of 65 said handle, and a resilient member engaging a recess in the end of said handle and yieldably bearing against the end of said cupped member.

3. The combination with a crank having an outwardly extending handle provided with a recess in the end thereof, of a sheet metal member sleeved upon said handle and having a spun portion engaging a contracted portion of said handle, and a resilient member positioned within said recess and yieldably bearing against the end of said sleeve member.

In testimony whereof I affix my signature in presence of two witnesses.

EMIL A. NELSON.
